(57) **CLAIM**

The ornamental design for a front panel for optoelectronic shelf, as shown and described.

DESCRIPTION

FIG. 1 is a front elevational view of the front panel for optoelectronic shelf with flip cover and fiber management cover being shown;

FIG. 2 is a front elevational view of the front panel of FIG. 1 with the flip cover and fiber management cover having been removed;

FIG. 3 is a left side elevational view thereof, the right side being a mirror image;

FIG. 4 is a top elevational view thereof; and,

FIG. 5 is a perspective view thereof.

The rear of the front panel for optoelectronic shelf forms no part of the claimed design.
